UNITED STATES PATENT OFFICE.

IRA W. KNIGHT, OF CRANSTON, RHODE ISLAND, ASSIGNOR TO GENERAL FIRE EXTINGUISHER COMPANY, OF PROVIDENCE, RHODE ISLAND, A CORPORATION OF DELAWARE.

AUTOMATIC MIXING AND DISCHARGING SYSTEM FOR PLURAL LIQUIDS.

Application filed November 5, 1924. Serial No. 747,980.

To all whom it may concern:

Be it known that I, IRA W. KNIGHT, a citizen of the United States, residing at Cranston, in the county of Providence and State of Rhode Island, have invented certain new and useful Improvements in Automatic Mixing and Discharging Systems for Plural Liquids, of which the following is a specification.

This invention relates to improvements in automatic mixing and discharging systems for plural liquids. More particularly it relates to fire extinguishing apparatus in which an acid solution, commonly known as the "A" solution, and an alkali solution, called the "B" solution, are maintained separate until discharge, whereupon they mix and react chemically to form an extinguishing agent, such as fire foam. In apparatus already proposed, the liquids are stored in separate containers from each of which a siphon leads to a common outlet. In order that these siphons may start working upon the opening of said outlet, it is necessary that they be duly filled with some liquid. The liquid of the container may rise in the intake leg, but it remains to fill the discharge leg of each, i. e., to prime it, preferably with some neutral liquid. This is accomplished by opening the crest of each siphon, pouring in the neutral liquid up to the desired level, and then closing the crest securely so that each is sealed air-tight. If the level of priming is not high enough in the discharge legs, or if either vent is left open by oversight, or leaks, the siphonic action cannot occur. And unfortunately such a condition will not be apparent until the need of action arises.

The present invention provides a specific form of siphonic apparatus, in which the element of danger due to human oversight or negligence is greatly reduced. Among its objects are the arrangement of the siphons in such manner and with suitable connections so that they become charged or primed simultaneously with the filling of the containers. Another object is to provide apparatus requiring only one vent, and to provide a plug for this vent, which, unless properly seated, will assume such a position as to indicate that it has not been replaced tightly in the vent hole.

These objects are attained by having one

siphon, preferably that in the "B" or non-corrosive solution, wholly submerged when the containers are fully charged, and having a communication from near its top to the discharge leg of the other siphon. The latter preferably rises from the "A" solution and descends through the "B" solution, and hence this connection can conveniently be made. At the crest of this latter siphon is the single vent, for the two siphons, and this is closed by a plug which in the illustrated embodiment of the invention is affixed to and forms a part of the cover that tops the containers. With this cover and plug removed, the liquids are poured into their respective containers until the desired level is reached. The acid or "A" solution simply rises in the entrance leg of its siphon, pushing the air out through the vent, until it stands at the same height in that leg and in the tank. When the "B" solution is poured in, this liquid similarly rises in the entrance leg of its siphon until its crest is reached, whereupon it flows over this crest into the discharge legs of both siphons, they being preferably connected at their lower extremities by entrance into a common discharge pipe. Air in the upper part of the shorter siphon may escape through the said communication between the discharge legs, and thence through the vent. When the "B" solution has risen in the container to the desired level the discharge legs of both siphons will be sufficiently filled, as well as their common outlet pipe. The vent plug is then to be replaced, and this must be screwed home or else the tank cover will sit askew, or will be above the top edge of the tank, thus giving warning, by its improper position, that complete replacement of the plug has not been effected. Thus the invention eliminates the danger of the siphon legs being not sufficiently primed by making the legs self priming, and greatly lessens the equally disastrous danger of failure to replace the vent plug, by making such failure evident to one glancing even casually at the supposedly charged apparatus.

It is intended that the patent shall cover, by suitable expression in the amended claims, whatever features of patentable novelty exist in the invention disclosed.

In the accompanying drawings the single figure is an elevation showing, in section, a

tank containing the two liquids in separate compartments, with cover and vent plug associated therewith, and in view uncut, the siphons, their connections, and the common 5 discharge.

Referring to the drawings, the tank is divided into two compartments 8 and 10, by a partition 14, to form separate containers for the two liquids; the acid solution being 10 in the compartment 10 having a lead or other non-corrosive lining 16. From this latter container rises the entrance leg 18', also non-corrosive, of the siphon 18. As illustrated this curves over the partition 14, and to have 15 a minimum of piping exposed to corrosion, descends through the alkali solution to the connection 20 with the common pipe 21. This latter has one or more single outlets controlled preferably by some thermo-responsive means, as an automatic sprinkler 20 head 22. Only one such outlet is illustrated, and this is closed by the containers, as would be suitable where the containers are to be placed close over the vat or other thing which 25 is to be protected, for this is the position for quickest and best action.

The other siphon, 12 for the "B" solution, has the bottom of its entrance leg 12' at the same level as the entrance leg 18' of the "A" 30 solution siphon, but its crest is arranged below the level at which the charge of "B" solution is desired to stand when ready for action. Its discharge leg 12" likewise descends through the alkali solution to the connecting pipe 20, and common discharge 21. It is connected to the discharge leg 18" of the longer siphon by a pipe 24 near the crest of siphon 12. This cross connection need 35 not be actually at the crest of the shorter siphon, as apparatus embodying the invention has operated satisfactorily with this connection as low as one-third the way down from the top of the "B" solution siphon. It is desirable that it be located near the 40 crest, however, as this prevents the leaving of any appreciable air space in the shorter siphon, and allows the liquid to rise and to stand high enough in its discharge leg to insure successful siphonic discharge when the 45 outlet through sprinkler 22 is opened. In certain cases, as where the outlet of the siphon is a considerable distance below the liquid level, this connection may be below the tank and still be high enough to be effective. In 50 fact it may be omitted if the discharge leg above the outlet is long enough to create sufficient suction to pull the liquids over the crests of their respective siphons when the common outlet is opened.

At the top of the siphon 18, is a vent 55 26 through which the air from both siphons escapes as the liquids are poured into their containers, and rise in the two siphons, but which must be tightly closed when the charging is completed. The closure for this vent

is a plug 28. This is fastened to the cover 30, whose peripheral flange 30' fits nicely around the top edge of the tank. This flange is less deep than the linear distance traveled by the plug in being screwed into the vent, so that if 70 through carelessness the plug is left merely placed on the edge of the vent, the flange will not be below the top of the tank, thereby disclosing to an observer that neither it or the plug have been properly replaced. By making a mark on the tank wall to indicate where the lower edge of the flange should be when the plug is tight, observation of the tank will readily show whether the plug is fully in, or is in position where air leakage may occur sufficient to prevent action of the siphon. As a further means to warn an observer that the plug has not been replaced, the end of the plug may be misshapen as at 28' so that if merely inserted in the vent hole it can 80 not seat evenly but will tilt, causing the cover to assume an awry position, easily noticed by anyone glancing at the tank.

In operation, when the sprinkler head, or other discharge valve is opened, the liquid in the two discharge legs 12" and 18" descends simultaneously into the pipe 20 and thence through the outlet. This first discharge is only "B" solution, but as this liquid sinks in both discharge legs it pulls over the liquids in the entrance legs in accordance with the siphonic principle, so that almost immediately following the opening of the outlet both solutions will be discharging together. And this simultaneous discharge will continue until the level in each container reaches the lower end of its respective entrance leg. The difference in length of pipe travelled by the liquids is so small that the excess of frictional resistance in the longer siphon is negligible. Accordingly, since the effective heads of the liquids are equal, they are emptied together in the same time. The liquids can be made of proper relative strength, as by using the acid in a suitable degree of dilution, to make the uniform discharge rate suitable for the chemical reaction. Or, if a discharge in some other ratio is desired the size of pipes and size and arrangement of containers can be varied accordingly. The connection 24 is so small in cross section that the opportunity for transfer of one liquid into the discharge leg of the other is of no consequence. In fact, the flow of the liquids downward past the small openings of the connecting pipe 24, probably acts with sufficient suction to establish a partial vacuum in the connection itself, and thus to prevent any mixing of the liquids 105 at this point.

Although but one outlet 22 is shown in the accompanying drawings it will be understood that the discharge pipes 12", 18" from the siphon may lead to a greater distance from the containers and may have 110

more than one outlet at each of which there is opportunity, as at 20, for the two liquids to flow into a single pipe 21 and to a discharge controlling device, as at 22, which may be 5 the occasion for setting the apparatus into action. In any such case the length of pipe 21 leading from the place where the discharging liquids come together has been found to work best when it is not long 10 enough for any considerable reaction to occur with generation of gas within it. For example, where the pipe 21 is a full size extension of outlet piping having $1\frac{1}{4}$ inches diameter, it is found that its outlet should 15 be reached in not exceeding 15 to 18 inches after the liquids have come together. Obviously this length may vary with circumstances, among which are the head, the size of pipes, and the vigor of chemical action 20 occurring after the liquids come together.

I claim:

1. An automatic mixing and discharging system for plural liquids comprising the combination, with separate containers for 25 said liquids, of a siphon for one of the containers rising above the normal level of its liquid, having a crest vent and a closure therefor; a siphon for the second container having its crest below the normal level of its 30 liquid; means connecting the discharge legs of said siphons, whereby the two discharge legs are primed by the filling of the second container to normal level; and a common valved outlet whose opening effects simultaneous discharge of both siphons. 35

2. An automatic mixing and discharging system for plural liquids comprising the combination, with separate containers for 40 said liquids, of a siphon for one of the containers rising above the normal level of its liquid, having a crest vent and a closure therefor; and a siphon for the second container having its crest below the normal level of its liquid; the discharge legs of the 45 said siphons having a common outlet with

control valve normally closed at their lower ends and having communication with each other near the crest of the submerged siphon whereby the discharge legs of both siphons are primed by the filling of the second 50 container to normal level; the opening of said valve effecting simultaneous discharge of both liquids.

3. An automatic mixing and discharging system for plural liquids comprising the 55 combination, with separate containers for said liquids, one of which has a removable cover, of siphons for the liquids having connections between their discharge legs, a valved outlet common to both siphons and 60 one of them adapted to have its discharge leg filled from its container through its intake leg, whereby upon filling the containers the said siphons are primed; a crest vent in the other siphon; and a removable 65 plug closure for said vent associated with said cover so that the position of the closure plug in respect to being seated and closing the vent is indicated by the position of said cover with respect to the container. 70

4. An automatic mixing and discharging system for plural liquids comprising the combination with their separate containers, of siphons of differential crest height, one being above and the other below the level of 75 its liquid when its container is normally filled, whereby upon the filling of the container whose siphon has the higher crest, its discharge leg is unaffected; a union between the discharge legs of the two siphons whereby upon the filling of the container whose siphon has the lower crest, both discharge legs are primed; and a common outlet for 80 both discharge legs having a closure adapted upon being opened to effect simultaneous discharge of both liquids. 85

Signed at Providence, R. I., this 24th day of October, 1924.
